UNITED STATES PATENT OFFICE.

LEWIS J. CLAPP, OF CLAREMONT, NEW HAMPSHIRE, ASSIGNOR TO SULLIVAN MACHINERY COMPANY, A CORPORATION OF MASSACHUSETTS.

CONTROLLING MECHANISM.

Application filed October 14, 1921, Serial No. 507,775. Renewed August 26, 1927.

My invention relates to controlling mechanisms.

It has for its object to provide an improved controlling mechanism and more especially to provide an improved controlling mechanism for a compressor or the like whereby the power supply to the compressor driving engine is controlled in an improved manner.

10 In the accompanying drawings I have shown for purposes of illustration one embodiment which my invention may assume in practice, the same being illustrated as applied to a compressor driven by a gas engine.

15 In these drawings,—

Fig. 1 is a side elevation of a compressor mechanism equipped with this form of my invention.

20 Fig. 2 is a detail view partially in elevation and partially in section and showing the controlling mechanism.

Fig. 3 is a detail sectional view showing the engine throttle valve.

25 Fig. 4 is a detail sectional view on line 4—4 of Fig. 1, showing one of the unloading mechanisms.

In this illustrative construction I have shown a portable compressor mechanism of 30 the truck supported type mounted on a wheeled truck 1 and including a vertical compressor 2 driven by a gasoline motor 3 and discharging into a receiver 4, the compressor herein being supplied with usual 35 suction inlet valves 5 operable by usual unloading plungers 6.

In my improvement, it will be observed 40 that the motor 3 carries a governor 7 herein operatively connected to a shaft 8 driven by the motor and of any desired form adapted upon excessive motor speed to project a normally retracted plunger 9, shown in Fig. 2, to the right to engage a pin 10 carried on a disk 11 which is operatively connected 45 to a shaft or pivot 12 on a usual normally open, ported valve 13, disposed in the fuel supply conduit 14 leading to the motor, and thereby, through moving the ported valve to closed position, cut down the speed of the 50 motor to the desired idling speed.

Cooperating with this governor operated 55 controlling mechanism is also controlling mechanism responsive to receiver pressure and also operating upon the valve 13. This mechanism, generally indicated at 15, is of

the type described and claimed in my Patent No. 1,473,598, dated Nov. 6, 1923. To this mechanism terminal or receiver pressure is supplied through a usual pilot valve 16 and a pipe 17 which in turn communicates with a chamber 18 from which receiver pressure is supplied to a cylinder 19 to propel a piston 20 longitudinally of that cylinder and thereby push a spring connected normally retracted member 21, carried on 60 the piston, into engagement with a pin 22 on the disk 11 to move the valve 13 to idling position; pressure fluid at the same time being supplied through a valve 23, a reduced portion 24 on the piston 20, and piping 25, 65 to the suction valve plungers 6 to open the valves 5 to unload the compressor. As in my previous application, when the receiver pressure falls below a predetermined point, the piston 20 moves backward first releasing the pin 22 to let the motor come up to speed and thereafter, by bringing the reduced portion 24 into communication with a port 26, exhausting the air beneath the plungers 6 to load the compressor. It will 70 be observed that the parts 18, 19, 20, 21, 23 and 24 constitute a servo-motor for actuating the shaft 12 through engagement of the plunger 21 with the pin 22.

As a result of my improvement it will be 75 observed that means are provided whereby not only is the fuel supply valve of the motor controlled by an excessive speed governor in such a manner as to decrease the fuel supply automatically whenever the motor speed is unduly increased, but that the 80 same valve is further controlled by cooperating controlling means responsive to receiver pressure which act automatically to cut down the fuel supply to the motor and thereby reduce its speed whenever the compressor is unloaded and which further cause the motor to be brought up to speed before the compressor is again loaded.

While I have in this application specifically described one form which my invention may assume in practice, it will be understood that this form of the same is shown for purposes of illustration and that the invention may be modified and embodied in 90 various other forms without departing from its spirit or the scope of the appended claims.

What I claim as new and desire to secure by Letters Patent is:

1. In a compressor system, in combination,

tion, a compressor, an internal combustion compressor driving engine, and controlling means comprising a cylinder, a piston therein, an engine intake throttle actuated by the piston adjacent the limit of movement of the latter, fluid operated compressor unloading means supplied with pressure on initial movement of said piston and vented by said piston as the latter returns to its initial position, and speed responsive means also controlling said intake throttle valve.

2. In a controlling mechanism for a compressor system comprising a compressor and an internal combustion driving engine therefor, in combination, a valve controlling the fuel supply to said engine, means operative on fluid supply thereto to unload a compressor and operative on release of fluid so supplied to permit reloading, and means for controlling such fluid supply and exhaust including a member reciprocable under fluid pressure and constituting an exhaust controlling valve, said reciprocable member being operative to control said fuel controlling valve in the interval between unloading of the compressor and its reloading.

3. In a controlling mechanism for a compressor system having a driving motor, a compressor and a pressure fluid actuated unloader for the compressor, in combination, controlling means for the motor including a controlled element, a servo-motor for actuating the same, means whereby a portion of said servo-motor operates as a control for the fluid pressure of said unloader and controls the loading operation thereof, and speed responsive means also for controlling said controlled element.

4. In a controlling mechanism for a compressor system having a driving motor, a compressor and a pressure fluid actuated unloader for the compressor, in combination, controlling means for the motor including a controlled element, a servo-motor for actuating the same, means whereby a portion of said servo-motor operates as a control for the fluid pressure of said unloader and controls the loading operation thereof, and speed responsive means also for controlling said controlled element independently of said servo-motor.

5. In a controlling mechanism for pumping apparatus which includes a compressor and a driving motor therefor, in combination, a throttle for said motor, a speed governor adapted to move said throttle and comprising a throttle moving element movable rectilinearly in a plane to which the axis of said valve is substantially perpendicular, a compressor discharge pressure controlled means including a longitudinally movable throttle actuating member movable rectilinearly in a path substantially parallel to the direction of movement of said element, and means for transmitting the

movement of said member to said throttle including a pivoted member, whereby movements of the speed governor and the longitudinally movable member of the pressure fluid device in opposite directions move the 70 throttle in the same direction.

6. In a controlling mechanism for pumping apparatus which includes a compressor and a driving motor for the compressor, controlling means for the driving motor 75 whereby the latter is controlled in accordance with the compressor discharge pressure and also by speed responsive means, including a pivoted throttle valve and controlling means for the latter including a member 80 movable by compressor discharge pressure and an element movable in accordance with variations in speed of the compressor driving motor, said member and element having axes disposed in a common plane to which 85 the pivotal axis of the throttle valve is substantially perpendicular.

7. In a controlling mechanism for a compressor system having an internal combustion driving engine, a compressor, and a 90 fluid pressure operated unloader for the compressor, in combination, controlling means for said engine including a fuel intake throttle valve, a servo-motor for actuating the same, and means whereby a portion 95 of said servo-motor operates as a control for the fluid pressure for said unloader and controls the loading operation thereof.

8. In a controlling mechanism for a compressor system having an internal combustion driving engine, a compressor, and a fluid pressure operated unloader for the compressor, in combination, controlling means for said engine including a fuel intake throttle valve, a servo-motor for actuating the same, and means whereby a portion 105 of said servo-motor operates as a control for the fluid pressure for said unloader and controls the loading operation thereof, and speed responsive means for controlling 110 said intake throttle valve.

9. In a controlling mechanism for a compressor system comprising an internal combustion motor, a compressor, and an unloader therefor adapted for fluid pressure 115 control, the combination including motor controlling means including a fuel intake throttle valve, speed responsive actuating means therefor, and a servo-motor for independently actuating said throttle valve, said 120 servo-motor being provided with valve means initially operated by fluid pressure and controlling the fluid pressure for the unloader.

10. In a controlling mechanism for a compressor system comprising an internal combustion motor, a compressor, and an unloader therefor adapted for fluid pressure 125 control, the combination including motor controlling means including a fuel intake 130

throttle valve, speed responsive actuating means therefor, and a servo-motor for independently actuating said throttle valve, said servo-motor including a piston having a circumferential groove controlling the exhaust of fluid pressure supplied to the unloader.

11. In a compressor controlling mechanism, a compressor, means for loading and unloading the same, a driving engine for said compressor having a controlling valve, means for moving said valve toward closing position when the compressor is unloaded and opening the same prior to loading said compressor including a valve actuating member whose movement also controls the loading of the compressor, and an independent engine speed responsive means likewise controlling said valve.

12. In a compressor controlling mechanism, a compressor having inlet valves, a driving engine therefor having a fuel conduit and a valve therein, and means for operating said valve including a plurality of pins movable with said valve and a plurality of plungers engageable with said pins, one of said plungers being movable in response to variations in engine speed, and the other in response to variations in compressor terminal pressure.

13. In a controlling mechanism for a compressor system having a driving motor and compressor, in combination, controlling means for the motor comprising a rotatable element having portions extending laterally and on opposite sides of the axis thereof, a speed responsive device adapted to engage one of said portions, and a device responsive to compressor pressure fluid engaging the other projection for controlling said motor controlling means.

14. In a controlling mechanism for a compressor system having a driving motor and compressor, in combination, controlling means for the motor comprising an element having lateral portions each movable in a predetermined path, and means adapted to engage and actuate said portions and disposed substantially tangential to certain portions of said paths.

15. In combination, a compressor, a driving motor therefor, and means for controlling said motor including speed responsive and pressure fluid devices, and an element controlled thereby for controlling said motor, said devices having actuating elements movable in opposite directions to produce independently of each other the same effect upon said controlled element.

16. In combination, a compressor, a driving motor therefor, speed responsive and pressure fluid devices for controlling said motor, and an element controlled thereby for controlling said motor, said devices having elements movable in substantially parallel directions but having their longitudinal axes

disposed laterally of each other and which are operable to effect control of said elements independently of each other.

17. In combination, a motor, and means for controlling the same comprising a power controlling element, and a plurality of automatically and independently operative means each adapted directly to control said element, said means having their longitudinal axes disposed laterally of each other and movable in opposite directions to produce a like effect thereon.

18. In combination, a compressor, a driving motor therefor, speed responsive and pressure fluid devices directly and independently controlled by each of said devices, and an element for controlling said motor, said devices having elements arranged to cooperate with said motor controlling element and movable in parallel directions but having their longitudinal axes disposed laterally of each other.

19. In combination, a compressor, a driving motor therefor, speed responsive and pressure fluid actuating devices, and an element controlled by each of said devices for controlling said motor, each of said devices being capable of taking simultaneously their full operative position whereby a like effect is produced on said controlled element.

20. In combination, a compressor, speed responsive and pressure fluid devices, and an element adapted to have a like controlling effect produced thereon by each of said devices, said devices being each capable of taking simultaneously their respective full operative position while said effect is being produced.

21. In combination, a compressor, speed responsive and pressure fluid devices, and an element adapted to have a like controlling effect produced thereon by each of said devices, said devices being capable of taking simultaneously their respective full operative position while said effect is being produced and each of said devices having movable elements whose axes are laterally disposed to each other and are adapted to move in parallel directions.

22. In a controlling mechanism for pumping apparatus which includes a compressor and a driving motor therefor, said motor having a control element, in combination, a speed responsive device and a pressure fluid device each adapted to move the control element of the motor, said devices having members movable in substantially parallel but opposite directions whereby to move the control element of the motor in the same direction.

23. In controlling mechanism for pumping apparatus which includes a compressor and a driving motor therefor, said motor having a control element, in combination, a speed responsive device and a pressure fluid

device each adapted independently of the other to move the control element of the motor, said devices having members movable in substantially parallel but opposite directions whereby to move the control element of the motor in the same direction.

24. In controlling mechanism for pumping apparatus which includes a compressor and a driving motor therefor, said motor having a control element, in combination, a speed responsive device and a pressure fluid device each adapted independently of the other to move the control element of the motor, said devices having movable members whose longitudinal axes are disposed laterally of each other, said members being movable in substantially parallel but opposite directions and connected to the control element of the motor to move the said element in the same direction.

25. In combination, a compressor driven by a motor having a control element, a speed responsive device and a pressure fluid device each having a movable member for trans-

mitting motion to said control element, the said movable members being each provided with a lost motion connection with the said control element to enable the speed responsive device and the pressure fluid device to take simultaneously their full operative positions.

26. In combination, a compressor driven by a motor having a control element, a speed responsive device and a pressure fluid device each having a movable member, the axis of one movable member being laterally disposed with respect to the other, the said movable members further being each provided with a lost motion connection with the said control element whereby the control element may be moved by both devices in the same direction and whereby the speed responsive device and the pressure fluid device may take simultaneously their full operative positions.

In testimony whereof I affix my signature.

LEWIS J. CLAPP.

CERTIFICATE OF CORRECTION.

Patent No. 1,657,200.

Granted January 24, 1928, to

LEWIS J. CLAPP.

It is hereby certified that error appears in the printed specification of the above numbered patent requiring correction as follows: Page 3, lines 80 and 81, claim 18, strike out the words "directly and independently controlled by each of said devices" and insert the same to follow after the word "element" in line 82; and that the said Letters Patent should be read with this correction therein that the same may conform to the record of the case in the Patent Office.

Signed and sealed this 20th day of March, A. D. 1928.

Seal.

M. J. Moore,
Acting Commissioner of Patents.
